UNITED STATES PATENT OFFICE.

ELLSWORTH A. LA HAR, OF NEW BRITAIN, CONNECTICUT, ASSIGNOR, BY MESNE ASSIGNMENTS, TO PERKINS CORPORATION, OF HARTFORD, CONNECTICUT, A CORPORATION OF CONNECTICUT.

TURN-BUTTON FOR ELECTRIC SWITCHES.

SPECIFICATION forming part of Letters Patent No. 784,006, dated February 28, 1905.

Application filed May 24, 1904. Serial No. 209,549.

To all whom it may concern:

Be it known that I, ELLSWORTH A. LA HAR, a citizen of the United States, residing at New Britain, in the county of Hartford and State 5 of Connecticut, have invented a new and useful Turn-Button for Electric Switches, of which the following is a specification.

This invention relates to a turn-button which has an elastic means for connecting it 10 with the operating-spindle, whereby the button may be firmly fastened to the spindle and will hold a cover or plate in position without binding.

The object of this invention is to provide a 15 simple construction which is strong, durable, and very elastic.

The embodiment of the invention, which is illustrated by the accompanying drawings, has a thumb-piece, of insulating material, containing 20 a metallic socket which is formed of an angular tube and an angular cap with a flange, the insulation being molded about the socket when the thumb-piece is formed. In the socket is a headed block with a threaded opening 25 which is adapted to receive the thread on the end of the operating-spindle and a spiral spring which thrusts between the head of the block and the end of the cap.

Figure 1 of the illustrations shows a central vertical section of the turn-button. Fig. 30 2 shows a horizontal section on the plane indicated by the dotted line 2 2 on Fig. 1. Fig. 3 shows a side view of the thumb-piece, the angular tube, the headed block, the spiral spring, the flanged cap, and the spindle before the parts are put together.

The thumb-piece 1 is formed of insulating material in any approved design. This insulating material is molded about the socket, 40 which consists of an angular tube 2 and an angular cap 3, which is simply thrust upon the outer end of the tube, so the flange 4 will extend outwardly some distance from the ends of the socket. It is preferred that the tube and cap be hexagonal in cross-section and that one loosely fit the other. As a result of the angularity of the tube and cap, the

socket cannot rotate in the thumb-piece, and the flange prevents the socket from being pulled from the thumb-piece when in use. 50

Loosely fitting in the socket is a block 5, having a head that fits the opening in the tube and a shank that fits the opening through the end of the cap. It is preferred that the head of the block be hexagonal, so that it will not 55 rotate, but will have a free movement longitudinally of the tube. In the socket and thrusting against the head of the block and against the end of the cap is a spiral spring 6. This spring normally draws the block into the 60 tube. A threaded hole 7 is formed in the outer end of the block to receive the threaded end of the switch-spindle 8. The block is screwed onto the spindle by turning the thumb-piece. The turn-button is very simple to 65 manufacture and assemble. The block and the spring are quickly thrust into the tube and the cap easily placed upon the end of the tube. Then the socket is put in the mold, and the insulating material which forms the thumb-piece is molded about the angular tube and 70 flanged angular cap.

The invention claimed is—

1. A button having a thumb-piece of insulating material containing a socket which is 75 formed of a tube that is angular in cross-section and has a cap with a flange that is embedded in the thumb-piece, the socket containing a headed block and a spiral spring that thrusts between the head of the block and the 80 outer end of the cap, substantially as specified.

2. A button having a thumb-piece of insulating material containing a socket which is formed of a tube that is angular in cross-section and an angular flanged cap that is thrust 85 on the end of the tube, the socket containing a block that is held against rotation and a spring that thrusts the block toward the inner end of the tube, substantially as specified.

ELLSWORTH A. LA HAR.
